UNITED STATES PATENT OFFICE.

EDWARD L. DUNN, OF WORCESTER, MASSACHUSETTS, ASSIGNOR TO STANDARD PLUNGER ELEVATOR COMPANY, OF WORCESTER, MASSACHUSETTS, A CORPORATION OF MASSACHUSETTS.

ELEVATOR SYSTEM.

1,287,581.

Specification of Letters Patent. Patented Dec. 10, 1918.

Original application filed August 7, 1909, Serial No. 511,680. Divided and this application filed May 5, 1916. Serial No. 95,560.

To all whom it may concern:

Be it known that I, EDWARD L. DUNN, a citizen of the United States, residing at Worcester, in the county of Worcester and 5 State of Massachusetts, have invented certain new and useful Improvements in Elevator Systems, of which the following is a full, clear, and exact specification.

This invention relates to automatic elevator systems and has particular reference to 10 automatic signaling systems for dumbwaiters or elevators, wherein the car can be sent to any predetermined floor and automatically stopped when the floor is reached.

Where a dumbwaiter or elevator system 15 has a considerable number of stops to make and a long run, necessitating several cars, it has been found that more satisfactory operating results can be obtained where the 20 machines are all controlled by a single operator. In order to enable the operator to control one or more cars at the greatest efficiency, it is desirable to provide a signaling system, and such signaling system should 25 embody means whereby delays, not only at the operating station, but at the floors, may be avoided; and also a system not required to be manually controlled.

In carrying out the invention, I have provided 30 an automatic signaling system for such elevator systems wherein the operator can be signaled from any station when a car is desired for use, who will thereupon send a car to that floor. The arrival of the 35 car at the floor will be indicated to the operator and also to the attendant on the floor, and when the attendant is through with the car, an indication of such fact will be made to the operator so that he can send the car 40 to the next station, or back to a central distributing station. I have provided herein such a signaling system in combination with an automatic elevator wherein at the operating station is provided an indicator for 45 each car showing the progress of the various cars from floor to floor, an annunciator showing the floors at which the car is desired, an audible signal in addition to the visual annunciator for attracting the attention of the operator; and at the respective stations, signals, preferably audible, for notifying the attendant of the arrival of the 50 car, the whole being arranged to be auto-

matically controlled by the opening and closing of the well-room doors so that the operator need pay no attention to the re-setting of the signals, but simply to the signals themselves, and will at all times know just where each car is. The doors themselves, 55 may be unlocked automatically by the stopping of the car, so that the system will become more completely automatic. By such a system, delays at the floors and the operating station will be very much reduced, and a greater efficiency of the whole installation 60 obtained, as the operator will always know the condition of each car, and have nothing to do with restoring the annunciator or 65 signals.

The invention, with respect to one form 70 thereof, is shown in the accompanying diagram, wherein is shown an automatic signaling system for two machines having each three stops, the motor circuits being omitted for the sake of clearness, and also the control 75 for one machine.

D¹, U¹ and D², U², represent the main switch down and up solenoids of two machines which will be hereinafter referred to as No. 1 machine and No. 2 machine respectively, and I will first briefly describe the starting and stopping system for No. 1 machine, that for No. 2 machine, and as many others as may be desired being similar, but omitted for the sake of clearness. S¹, 85 S² represent starting switches for the two machines, located preferably at a control station distant from the cars and the floors to which the cars run, and also at this control station are located signals for attracting 90 the attention of the operator when a car is desired by the attendant at any floor, and signals for at all times indicating to the operator the locations of the various cars, and their condition, whether in service, or 95 ready for service.

T¹ and T² are main line switches from the former of which a wire H leads to up and down automatics L and M. From automatic M a wire V³ leads to a movable contact H⁴, 100 operated by the switch arm P to close circuit at H⁵, thence by wire V⁵ to down direction magnet K¹, thence to negative side of switch T'. The switch H⁴ is only momentarily closed, being opened automatically by means 105 not necessary to be described herein, but the

energization of magnet K¹, closes contacts J⁸ and thereby energizes main switch magnet D¹, closing the main motor circuit and starting the car downward. In similar manner, 5 the up magnet K is controlled by a switch H⁴ and contact H⁶ to send the car up, it being understood that one or the other of these switches is closed whenever the pointer P is moved. In order to stop the car at the pre- 10 determined floor, an arm O traveling with the car completes a stop circuit from the positive side of switch T' through switch X' (closed whenever the main switch is closed) and contact N and thence through one or the 15 other of wires R, R¹, R², to corresponding contacts controlled by the starting switch P, and bridged by the switch to negative side of line through resistance Y. When this 20 circuit is closed, the magnets D', U', K, K' are short circuited through a wire leading through resistance Y to arm P thence through wire R, R' or R² through contacts O³, O² or O¹ to arm O, its contact ring and wire leading through contact N to wire W¹² 25 connected through switch X' to positive side of switch T', thereby opening the main switch and stopping the machine. It will be seen that the switches J⁷, J⁸, close maintaining circuits, which hold the magnets energized, after the switches H⁴ have opened. 30 Also in a circuit to be controlled simultaneously with the magnets may be placed a door unlocking magnet Q, to unlock the door and permit it to be opened by the attendant 35 when the car has reached that floor, as shown in my Patent No. 987,673, dated March 21, 1911. Or other means will be provided for unlocking the door at which the car is to stop. This is desirable, in order that the signals for the attendant and operator may be 40 properly operated. By the combination of door unlocking means controlled by the stopping of the car, and the signal releasing devices controlled by the door, the system both 45 as to signals and control will be entirely automatic, and the operator will at all times know accurately, the condition of the system, and of each car.

F¹, F², F³ represent door switches for machine No. 1, and F⁴, F⁵, F⁶ corresponding door switches for machine No. 2. X¹ is a switch which closes as the main switch solenoid D¹ is energized, and X² a corresponding switch which operates in the same manner at machine No. 2 when solenoid D² is energized.

First describing the indicators, which are alike for each machine, there is provided a cross-head E¹, which is caused to move 60 across the faces of the sets of stationary contacts 1, 2, 3, G¹, H¹, H², H³, G³, G⁵, J¹, J², J³, as the machine moves in one or the other direction. These commutators will ordinarily 65 be driven by a worm shaft and traveling nut, as is well understood. In a similar manner,

the cross-head E² moves over corresponding sets of contacts 1, 2, 3, G², Y¹, Y², Y³, G⁴, G⁶, J⁴, J⁵, J⁶, for machine No. 2, and there will be as many similar sets of commutators and brushes as there are machines. T is a line 70 switch adapted to be connected with a source of low voltage current, and from the positive terminal of switch T a wire W¹ supplies current to the contacts G¹, G², etc. From G¹ a jumper on the brush E¹ conducts the current to the contacts 1, 2, 3, and thence the current passes through wires W² to an indicator I for machine No. 1, and thence by return wire W³ to the negative side of switch T. The indicator I preferably comprises a 80 series of flashlights, one for each floor, which will be lighted one after another as the brush E¹ travels over the contacts 1, 2, 3. For machine No. 2, a similar indicator I² supplied by wires W⁴ acts in the same manner. In 85 the position shown, car No. 1, is at the first floor, and car No. 2 at the second floor.

It is desirable to provide an audible signal to attract the attention of the operator to the annunciator signal, and I will now describe the annunciator circuits and then the audible signal circuits. From the positive side of switch T, wire W⁵ is connected to a bell or buzzer B located at or adjacent the operating station and starting switch, and 95 from the bell B, wire W⁶ leads to a series of floor push buttons P¹, P², P³. One of these buttons will be at each floor in a system where the cars are used to carry material from a central distributing station to the 100 several floors, or from these several floors back to the central station, or where cars run light in either direction between the central station and the respective floors. To enable the operator at any floor to call a car to that 105 floor and despatch it to another without return to the central station, the complete set of buttons P¹, P², P³ shown may be duplicated at each floor, so that the operator, when at floor 2, having received car No. 2, may 110 load it and then by pressing button No. 3, signal the operator to send this car to floor No. 3. It has been found in practice, however, with dumbwaiter systems such as this 115 invention is particularly adapted for, that greater efficiency is obtained by operating the cars from a central station, since in hotels, for instance, time is saved by sending different cars to different floors, rather than having one car stop at a number of different 120 floors to pick up or leave material. In most instances, therefore, it will only be necessary to have a single button at each floor. The circuit of push button P¹, for instance, leads by wire W⁷ to a lighting magnet B¹, and 125 thence by wire W⁸ to the negative side of switch T. The circuit of push button P² similarly leads to a lighting magnet B² to wire W⁹, and P³ to lighting magnet B³, there being as many magnets B¹, etc., as 130

there are floors. Upon magnet B^3 being energized, its armature closes a circuit from wire W^1 to contacts X^3, X^4 , to wire W^9 , and thence across contacts X^5, X^6 to wire W^7 , so that magnet B^3 will remain energized, even after the push button circuit has been opened, as it is only momentarily held closed. The opening of the push button circuit, does however, release the bell or buzzer. At the same time that the holding circuit of magnet B^3 is closed at contacts X^3 and X^4 , current is supplied to wire W^{15} and thence to the light 3 of the annunciator A , the remainder of the circuit being through wire W^2 to the negative side of switch T . It thus appears that upon the momentary closing of a push button one or the other of magnets B^1 , etc., is energized and a corresponding indication made at the annunciator A , from which the operator knows that a car is desired at that floor. At the same time the alarm B sounds, as will be understood, since the alarm is at first in series with the magnets B^1, B^2 , etc., but a single alarm and set of push buttons being required for any number of floors and machines.

Assuming that the operator's attention has been attracted by the bell and he has despatched No. 1 car to the third floor, contacts X^1 are closed, contacts X^7 are opened by the closing of the main switch, and the brush E^1 is moving toward No. 3 to contacts J^3, H^3 . As contact H^2 is engaged the floor bell does not ring, owing to the open circuit at contacts X^7 , but as the machine stops at the third floor, the bell B^6 is in circuit from positive side of switch T through wire W^5 to bell B^6 , to wire W^{10} , to contacts H^3, G^3 by a jumper on blade E^1 , wire W^{11} to contacts X^7 , X^9 which are now closed by the opening of the main switch, wire W^8 to the negative side of switch T . When the contacts X^1 were closed by the closing of the main switch in either direction, the controlling magnet A^1 was energized, its circuit being through contacts X^1 and wire W^{12} , resistance R to negative side of switch T^1 . As contacts X^1 open and the machine stops, the magnet A^1 is not deenergized, as it receives current through the door switches F^1, F^2, F^3 and magnet switch contacts X^{10} controlled by the magnet A^1 . The floor bell B^6 , therefore continues ringing until the door switch circuit is opened, which deenergizes the magnet A^1 and opens the bell circuit at contact X^9 . When the door is closed again, the bell does not ring as the magnet A^1 can only receive starting current through contacts X^1 , which remain open until the main switch closes, but the annunciator light is automatically extinguished by the closing of the door as follows:

As the contacts X^{11} are now connected, the high voltage current passes from positive side of switch T^1 through door switches F^1 ,

F^2, F^3 , contacts X^{11} and wire W^{17} , thence to magnet A^2 , and resistance R to the negative side of the line. This energizes the magnet A^2 and closes contacts X^{13}, X^{14} , making a circuit momentarily through extinguishing magnet C^3 , deenergizing the lighting magnet B^3 , thereby opening the annunciator circuit. It will therefore be seen that the annunciator circuit is not affected by the stopping, and that the light remains 70 lighted while the door is open, thus notifying the operator that the door is open at the floor where the car is stopped only, and as soon as the door is closed the extinguished light shows that the machine can 75 now be operated safely. The circuit of extinguishing magnet C^3 extends from positive side of switch T through wire W^1 , contacts X^3, X^4 , wire W^9 , extinguishing magnet C^3 , wire W^{13} , contacts J^3, G^3 , wire W^{14} , controlling magnet contacts X^{13}, X^{14} , wire W^8 , to the negative side of switch T . When the extinguishing magnet C^3 is energized the circuit of lighting magnet B^3 is opened 80 at contacts X^5, X^6 , and the lighting magnet 85 B^3 thus opens the circuit of extinguishing magnet C^3 at contacts X^3, X^4 , as well as the annunciator light circuit. Controlling magnet A^2 remains in circuit while the machine is at rest, but when the machine starts, 90 it is deenergized by the opening of contacts X^{11} . It will therefore be seen that the magnet A^1 sets the floor bell circuit to be completed at the proper floor by the brush E^1 bridging contacts H^1, H^2 or H^3 and contacts G^3 , and that this circuit is opened by 95 the opening of the door, but that the annunciator circuit at the operator's station remains in condition to give an indication not only while the machine is at rest with 100 the door closed, but while the door is open, being only extinguished when the door is closed after having once been opened. The other circuits for different floors and 105 different machines will be the same as those just described, and particular reference and explanation need not be made thereto. In the event of two cars arriving at the same floor simultaneously, the bell at that floor would ring until both the doors were opened 110 115 as the signal machines are cross-connected in parallel.

It is thought that the advantages of the system will be fully understood from the foregoing description, wherein it will be 120 seen that the system is completely automatic in operation after the floor push buttons have been operated. While bells have been shown at the various floors to notify the attendants of the arrival of the cars, in many 125 instances pilot lights may be shown where the noise of bells and buzzers would be objectionable. Such a system has a number of advantages, of which the principal one is that the attendants are automatically noti- 130

- fied that a car is waiting, and the operator is likewise automatically notified when the attendant is through with the car, while at the same time the annunciator is restored.
- 5 Thus the operator does not have to give attention to the annunciator, as each individual car takes care of its own annunciator, and there is no loss of time at the floors or at the operating station.
- 10 This application is a division of application Serial No. 511,680, filed August 7, 1909, patented May 23, 1916, No. 1,184,169, and the claims herein are consequently directed to the novel features of signal mechanism irrespective of the place or character of motor control.
- Having thus described my invention, I declare that what I claim as new and desire to secure by Letters Patent, is:—
- 20 1. The combination in an elevator system, of a call signal for indicating the destination of a car, a signal at the floor for automatically indicating the arrival of the car, means for releasing said signal upon opening of the door, and means for releasing said call signal upon closing of the door.
2. In an elevator system, the combination with a floor signal, of means traveling with the car for setting the floor signal circuit, 30 and means controlled by the opening of the main switch in stopping the car for energizing said signal.
3. In an elevator system, the combination with a floor signal, of means traveling with the car for setting the floor signal circuit, 35 means controlled by the opening of the main switch in stopping the car for energizing said signal, and means controlled by the well door for releasing said signal.
- 40 4. In an elevator system comprising a car, a plurality of floor stations and a central control station, the combination with means at the central station to indicate the location of the car relatively to the floor stations, of signal means at said central station for indicating to the operator there that the car is no longer needed at a given floor, said signal means being dependent for its actuation upon the arrival of a car at said floor and 45 the opening and closing of the elevator door thereat.
5. In an elevator signal system, the combination with a call signal at a fixed station for indicating at what floor a car is desired, a signal at the floor announcing the arrival of the car thereat, means for shutting off said signal at the floor upon opening of the elevator door and maintaining said signal shut off upon closing of the door, and means 55 whereby the closing of the elevator door at said floor is automatically indicated at said station to show that the car is no longer required at that floor.
- 60 6. In an elevator signal system, the combination with a signal at each floor adapted
- to announce the arrival of a car at that floor, an electric circuit for actuating said signal, control means for said circuit rendered effective only by the stopping of a car at said floor to operate said signal and announce the 70 arrival of the car, and means for shutting off said signal.
7. In an elevator system comprising a plurality of floor stations, the combination with a floor signal at one of said stations for indicating the arrival of the car thereat, of means for stopping the car at said floor, and means controlled by said stopping means for actuating said signal so as to indicate the arrival of the car at said station only 80 when the car stops there.
8. In an elevator system having a plurality of floor stations and a control station, the combination with a car adapted to stop at any of the floor stations, of a signal system therefor comprising a call signal at the control station adapted when actuated to indicate the floor at which a car is desired, means for shutting off said call signal, and means rendering said shutting off means ineffective to withdraw said call signal until 85 said car has stopped at the corresponding floor station.
9. In an elevator signal system, the combination with a visual call signal at a fixed 95 station for indicating the floor at which a car is desired, means for restoring said signal to show that the car is no longer required at that floor, and means for maintaining said restoring means ineffective until the 100 car has stopped at said floor.
10. In an elevator signal system, the combination with a call signal at a fixed station for indicating the floor at which a car is desired, a floor signal for indicating the arrival of the car at said floor, means for releasing both of said signals, and means for maintaining said releasing means ineffective until the 105 elevator door is moved.
11. In an elevator signal system, the combination with an annunciator signal at a fixed station adapted to be energized from any floor, a set of call signals corresponding to each floor at said station, means at each floor for energizing said annunciator and 110 call signals to draw attention and indicate the floor at which a car is desired, a floor signal indicating the arrival of the car at the floor, means for releasing said annunciator signal, means for releasing said floor 115 signal by opening of the elevator door, and means for releasing said call signal by closing of said door.
12. In an elevator system comprising a car, a plurality of floor stations, corresponding doors and a fixed central station, the combination of signal means at the central station to indicate that a car is wanted at a particular floor, means operable manually 125 at each floor station initially to give a signal 130

- indication at the central station, means to continue an indication there automatically, means to change such indication upon closure of a corresponding door subject to arrival of the car thereat and opening of said door, means to indicate at the central station the location of the car relatively to the floor stations, means to indicate at each floor station the arrival and stoppage of the car thereat, and means to change such indication upon the opening of a corresponding door.
13. In an elevator system comprising a car, a control station and a plurality of floor stations having doors, the combination with signal operating means at each floor station for indicating that a car is wanted at that floor, of a signal at each floor station for indicating the arrival of a car thereat, means for operating said signal upon the stoppage of the car at the corresponding floor, and means for maintaining said signal in operation until the elevator door at said floor is opened.
14. In an elevator system comprising a car, a plurality of floor stations and a central control station, the combination with signals at said control station for indicating the position of the car relatively to said floor stations, of signal means for indicating at said central station the condition of said car comprising signal means adapted to be actuated from said floor stations and means for preventing actuation of said signal means from a given floor station until the car has stopped at said station.
15. In an elevator system comprising a car, a plurality of floor stations, corresponding doors and a fixed central station, the combination of signal means to indicate at the central station the location of each car relatively to the floor stations, means to indicate at each floor station the arrival and stoppage of a car thereat, and means to change such indication upon the opening of a corresponding door.
16. In an elevator system comprising a plurality of cars, floor stations, corresponding doors and a fixed central station, the combination of signal means at the central station to indicate that a car is wanted at a particular floor, means operable manually at each floor station initially to give a signal indication at the central station, means to continue an indication there automatically, means to change such indication upon closure of a corresponding door subsequent to arrival of a car thereat and opening of said door, means to indicate at the central station the location of each car relatively to the floor stations, means to indicate at each floor station the arrival and stoppage of a car thereat, and means to change such indication upon the opening of a corresponding door.
17. In an elevator system comprising a car, a plurality of floor stations and a central control station, the combination with signals at said central station for calling and releasing the car, of means for operating said signals from said floor stations, and means preventing operation of said signals to indicate the release of the car except from the floor to which the car has been sent.
18. In an elevator system comprising a plurality of cars, floor stations, corresponding doors and a fixed central station, the combination therewith of signal means at the central station to indicate that a car is wanted at a particular floor, means to automatically indicate at each floor station the arrival and stoppage of a car thereat, and means to change such indication upon the opening of a corresponding door.
19. In an elevator system comprising a plurality of cars, floor stations, corresponding doors and a fixed central station, the combination of means to indicate at the central station the location of each car relatively to the floor stations, and means to indicate at the central station the closure of a door at a floor station subsequent to arrival of a car thereat and opening of said door.
20. In an elevator system comprising a plurality of cars, floor stations, corresponding doors and a fixed central station, the combination of signal means at the central station to indicate that a car is wanted at a particular floor, means to automatically indicate at each floor station the arrival and stoppage of a car thereat, and means to change such indication only upon opening the corresponding doors for all of the cars stopped at said floor.
- In testimony whereof I affix my signature, in presence of two witnesses.
- EDWARD L. DUNN.
